CANDLE

Lucius M. Crumrine, Jr., Burlingame, Calif., assignor to Bluegate Candle Company, Montara, Calif., a corporation of California

Filed July 5, 1966, Ser. No. 2,944

Term of patent 14 years

(Cl. D73—1)

rating my new design.

FIGURE 2 is an enlarged top plan view thereof, showing the longitudinal ridges formed thereon.

FIGURE 3 is an enlarged view of the candle partly in cross-section and partly phantomed, and showing particularly the details of the design in longitudinal section, the transverse circumferential sections being circular except for the longitudinal ridges.

I claim:

The ornamental design for a candle, as shown and described.
